SLIDING DOOR OPERATING MECHANISM
 Bruce B. Bidelman, Marshall, Raymond R. Martin, Albion, and George R. Millard, Tekonsha, Mich., assignors to Ronan & Kunzl, Inc., Marshall, Mich.
 Filed Mar. 11, 1966, Ser. No. 533,503
 16 Claims. (Cl. 49—360)

This invention relates to improvements in sliding door operating mechanism. The principal objects of this invention are:

First, to provide reciprocable drive mechanism for a sliding door in which the inertia forces incident to starting and stopping the door are cushioned to relieve the driving motor and mechanism from heavy impact loads.

Second, to provide yieldable door retarding members at the ends of the opening and closing motion travel of the door which cooperate with the driving mechanism to prevent excess loads from being applied to the driving motor and which yieldably cushion the stopping action of the door without imparting any reverse motion to the door such as would tend to move the door slightly from its opened or closed position.

Third, to provide a door supporting and travel limiting mechanism for a sliding door in which yieldably mounted brake shoes cushion the travel movement of the door and also actuate limit switches for de-energizing the power source for the door operating mechanism.

Fourth, to provide reciprocable driving mechanism for a power operated sliding door which is relatively inexpensive and easily adapted to doors of different widths and lengths of opening and closing motion.

Fifth, to provide reciprocable door operating mechanism for a sliding door which inherently opens at maximum velocity and which tends to close more slowly.

Sixth, to provide a door operating mechanism which includes a simple mechanical safety disconnect to prevent the door closing upon a person with sufficient force to injure the person.

Seventh, to provide a reciprocable door operating mechanism with motion cushioning brakes operative at the ends of the travel of the door, which brakes are automatically released by reverse starting motion of the door in either direction to relieve the driving mechanism of any load incident to overcoming the effect of the stopping brake.

Other objects and advantages of the invention will be apparent from a consideration of the following description and claims. The drawings of which there are two sheets illustrate a highly practical form of the operating mechanism as applied to a horizontally sliding vertical door.

FIG. 1 is a fragmentary elevational view of a door mounted in a door opening and adapted to be moved between open and closed position by operating mechanism of the invention.

FIG. 2 is a fragmentary top plan view of the operating mechanism shown in two sections and taken along the plane of the line 2—2 in FIG. 1.

FIG. 3 is a front elevational view of the operating mechanism, the view being broken into two sections and the driving motor being removed.

FIG. 4 is a vertical cross sectional view through the driving mechanism taken along the plane of the line 4—4 in FIGS. 1 and 2.

FIG. 5 is a fragmentary enlarged vertical cross sectional view taken along the plane of the line 5—5 in FIG. 4 and illustrating the supporting and braking and control mechanism adjacent the closing edge of the door with the door in closing motion.

FIG. 6 is a view of the mechanism shown in FIG. 5 with the door slowing and approaching closed position.

2

FIG. 7 is a view similar to FIGS. 5 and 6 showing the door at the start of its opening motion.

FIG. 8 is a fragmentary detailed elevational view of the connection between the door operating mechanism and the movable support for the door.

As appears in FIG. 1 a door 1 is mounted for horizontal sliding motion in a wall 2 to open and close the doorway formed by the frame members 3. The door slides into or behind the wall 2 to the open position indicated at 1A and is driven by means of mechanism of the invention which may be enclosed in the wall or within an upper lintel housing 4 extending across and beyond the doorway.

The door supporting mechanism consists of a door supporting track indicated generally at 5 in FIG. 4 and including an upper structural support 6 in the form of an angle shaped member and a lower channel shaped portion 7 secured to the upper angle as by bolts 8. The channel portion 7 has inwardly turned opposed lower supporting flanges 9 which receive and support pairs of rollers 10—10 mounted on cross pins or axles 11. Two pairs of the rollers 10 are provided, one near the closing edge of the door and one near the opposite edge of the door. The rollers are connected by a door support bar 12 which projects downwardly between the flanges 9 and is provided at each end with a pair of depending ears 13 spaced longitudinally of the bar. The upper edge of the door 1 is provided with hanger brackets 14 with upstanding lugs 15 projecting between the pairs of ears and secured thereto by cross pins 16.

Secured to the end of the supporting track corresponding to the open position of the door is a mounting bracket or housing 17 (see FIGS. 2 and 3) which supports a drive shaft 18 transversely of the track. The drive shaft 18 carries a drive pulley 19 in closely spaced relation to the track and a reversible electric motor 20 operating through a gear box 21 are conventionally illustrated and mounted in driving relation to the shaft 18 adjacent to the track.

The pulley 19 reversely drives a flexible belt 22 and in the example illustrated the belt and pulley are of the V-belt type. The belt 22 is formed into a loop extending longitudinally of the track and trained around an idler pulley 23 positioned intermediate the ends of the track. The idler pulley is carried by a pin or axle 24 supported in an upwardly facing channel shaped idler pulley bracket 25 positioned or supported on the lower horizontal flange 26 of the structural angle portion 6 of the track. The bracket slides on the flange 26, being guided by bolts or pins 27 projecting upwardly from the flange 26 through slots 28 in the bracket 25 to longitudinally guide the ends of the bracket. The right end of the bracket has a cross wall 29 through which a guide pin 30 (see FIG. 3) is slidably extended. The guide pin 30 is fixedly connected to an angle bracket 31 secured to the flange 26 and has adjustable stops or nuts 32 thereon which form abutments for a compression spring 33 positioned around the pin and bearing against the crosspiece 29.

As will be apparent any unusual tension in the belt 22 will compress the spring 33 thus relieving the tension and releasing the frictional driving engagement between the belt and the drive pulley 19 so that the door will stop even if the motor 20 continues to operate. In the particular example illustrated the belt is formed into a loop having an upper idling reach 34 and a lower driving reach 35 by connecting the ends of a straight length of belting 36 by means of crimped connectors 36 (see FIG. 8) which engage the ends of the belting and have ears 37 that are overlapped and secured to each other and to the top of the bar 12 as by the cap screw 38. The lower driving reach 35 of the belt extends within the channel shaped portion 7 of the rail to the lower periphery of the idler pulley 23 which projects downwardly through a slot 138.

provided therefor in the pulley support bracket, upper rail portion 6 and lower rail portion 7.

Positioned adjacent each end of the track 5 is a retarding brake shoe and limit switch assembly indicated generally by the numeral 39. The retarding brake and switch assemblies are identical and reversed so that a description of one will be sufficient to an understanding of the mechanism. Secured to the top of flange 26 is a retarding plate supporting bracket 40 having longitudinally spaced upstanding ears 41 at each end with downwardly turned flanges 42 at their outer sides. The bracket plate 40 is secured to the track flange by a pair of upstanding studs 43 passed through the bracket and having nuts 44 on their upper ends which compress brake or retarding springs 45 to yieldably urge the brake shoe supporting brackets toward the track flange 26. The retarding plate supporting brackets are fixed by the studs 43 against longitudinal motion on the track. Supported between the upstanding ears 41 and their downturned outer flanges 42 are cam pins 46 which extend through and longitudinally and vertically guide a generally rectangular brake shoe plate 47. The plate 47 has cam slots 48 formed therein which receive the pins 46 and which are inclined upwardly or away from the track and toward the center of the track. As appears more clearly in FIG. 7 the cam slots 48 have longitudinal dwell portions 49 at their inner ends which receive the pins 46 at one limit of travel of the brake shoe. The brake shoe has a longitudinally inwardly facing cam surface 50 positioned to engage and cammingly coact with the door supporting rollers 19 so that motion of the door and its rollers against the brake shoe presses the brake shoe upwardly. The brake shoe or plate 47 is biased longitudinally outwardly and downwardly toward the end of the track by a light tension spring 51 anchored to the plate by the screw 52 and having its other end connected to the outer stud 43.

Positioned longitudinally inwardly of each brake shoe support bracket is a limit switch mounting bracket 53 having a bottom flange 54 secured to the flange 26 of the structural angle portion of the track and having an upturned flange 55 on which is mounted an electrical switch 56 having an operating roller or element 57. The flange 54 of the switch bracket is slotted as at 58 in FIG. 2 to pass a trip finger or switch actuating portion 59 formed on the inner end of the brake shoe. Upward movement of the brake shoe under the influence of the door rollers away from the roller supporting flanges 9 moves the brake shoe and the shoe supporting bracket against the compression of the retarding spring means 45 and also actuates the limit switch 56. While in the example illustrated the brake shoe and brake shoe supporting bracket are mounted vertically above the track it will be apparent that other angular positions of the brake shoe and switch mechanism relative to the axis of the track are possible.

FIGS. 5, 6 and 7 illustrate the action of the retarding shoe on the door. In FIG. 5 the roller 10 is rotating and the bar 12 is moving the door toward closed position. The switch actuating finger 59 is down and the actuating element 57 of the switch is in unactuated position. The shoe 47 is drawn longitudinally outwardly of the track 5 and the pins 46 are positioned in the keeper or dwell portion 49 at the inner ends of the slots 48. As the edge of the door approaches its stop position such as the jamb indicated conventionally at 60 the roller moves the brake shoe upwardly causing the finger 59 to actuate the switch. Being vertically obstructed by the dwell portions 49, upward motion of the shoe lifts the pins 46 causing the brake shoe supporting bracket 40 to be raised against the compression of springs 45 thus applying braking pressure to the roller 10. The roller 10 accordingly slides rather than rotates between the brake shoe and its supporting flange 9 applying a retarding pressure which slows the door and prevents a heavy impact against the jamb. Note that the position of the pins in the keeper portion 49 prevent any reverse camming action which would tend to

open the door once it is stopped by the jamb 60. When the door is next actuated toward open position as is shown in FIG. 7, the frictional force of the roller 10 on the bottom of the brake shoe moves the brake shoe 47 with it longitudinally to the right causing the plate and its inclined cam slots 48 to move up on the pins. This immediately releases the door retarding pressure on the roller and the door starts easily toward open position. This reduces the starting load on the motor 20. The same action occurs with both brake and limit switch assemblies 39 at the ends of the travel of the door.

It is pointed out that the lower working reach 35 of the belt is under direct tension between the drive pulley 19 and the connection 38 to the door when the door is opened, the spring 33 having moved the idler roller to initially tension the entire belt. The entire output of the drive roller is thus available to quickly start the door in its opening motion. Should the inertia of the door apply sufficient tension to the idler support bracket 25 the spring 33 may yield slightly and thus aid the motor in picking up the opening load of the door. As was previously noted the closing motion of the door is effected by tension in the upper reach 34 of the belt loop so that any obstruction such as might be caused by a person stepping into the path of the moving door will apply twice the closing tension of the belt to the idler pulley 23 so that the spring 33 is compressed and the frictional driving engagement of the belt with the driving pulley is released. The drive to the door thus incorporates an automatic safety feature preventing injury to persons using the door.

The limit switches 56 may be connected with the motor along with another control switch such as a switch mat 61 in a well known manner to cause the door to open and close as desired. While the operating mechanism for the door has been shown as associated with the upper edge of a suspended door, the brake and automatic stopping features of the operating mechanism are equally applicable to drive connections positioned at the bottom of the door.

What is claimed as new is:

1. Sliding door operating and supporting mechanism including a door supporting track to support a door in open and closed positions relative to an upright jamb, rollers spaced along said track and connected to the top of the door, a drive shaft extending transversely of said track adjacent an end thereof and having a reversible drive including a motor connected to the shaft, said mechanism being characterized by a drive pulley connected to said shaft, an idler pulley support longitudinally slidably mounted on said track and having an idler pulley rotatably mounted on said pulley support, first spring means biasing said support and idler pulley away from said drive pulley, a belt trained around said pulleys and urged to frictional driving engagement with said drive pulley by said first spring means, means connecting a reach of said belt to the top of said door, door opened and door closed retarding plates disposed in spaced relation along said track to be engaged by one of said rollers in the opened and closed positions of said door respectively, retarding plate supporting brackets vertically movably mounted on said track adjacent said retarding plates and spring loaded by second spring means toward said track, said supporting brackets being connected to said retarding plates to load said second spring means when one of said rollers engages one of the plates, switch operating projections on said retarding plates, and limit switches carried by said track and having operating elements positioned to be actuated by said projections, said switches being adapted to be electrically connected

- to said motor to stop the motor in door opened and door closed positions.
2. Mechanism according to claim 1 in which said door is connected to the reach of said belt which is driven in tension upon opening motion of said door.
3. Mechanism according to claim 2 in which said belt is of V-shaped cross section and said pulleys are corresponding V pulleys mounted on horizontal axis, and the lower reach of said belt is tensioned upon opening motion of the door.
4. Mechanism according to claim 1 in which said retarding plates are longitudinally slidably mounted on said brackets, means limiting the sliding motion of said plates along downwardly and longitudinally outwardly directed paths toward the ends of said track, and third spring means biasing said plates outwardly toward the ends of said track.
5. Mechanism according to claim 2 in which said retarding plates are longitudinally slidably mounted on said brackets, means limiting the sliding motion of said plates along downwardly and longitudinally outwardly directed paths toward the ends of said track, and third spring means biasing said plates outwardly toward the ends of said track.
6. Mechanism according to claim 4 in which said means limiting the sliding motion of said plates on said brackets have end portions at their longitudinally inner ends preventing vertical motion of the plates relative to the brackets and into which said plates are biased by said third spring means.
7. Mechanism according to claim 5 in which said means limiting the sliding motion of said plates on said brackets have end portions at their longitudinally inner ends preventing vertical motion of the plates relative to the brackets and into which said plates are biased by said third spring means.
8. Sliding door operating and supporting mechanism including a door supporting track to support a door in open and closed positions relative to an upright jamb, rollers spaced along said track and connected to the edge of the door, a drive shaft extending transversely of said track adjacent an end thereof and having a reversible drive including a motor connected to the shaft, said mechanism being characterized by a drive pulley connected to said shaft, an idler pulley mounted on said track, a drive member loop trained around said pulleys, means connecting a reach of said drive member loop to said door, and door opened and door closed retarding means disposed in spaced relation along said track to be frictionally engaged by parts carried by the door in approaching the opened and closed positions of said door respectively, said retarding means having springs loaded as the parts approach open and closed positions of the door, said springs being released by initial movement of the parts on the door away from opened and closed positions of the door.
9. Mechanism according to claim 8 in which said retarding means comprises, retarding member supporting brackets mounted on said track for movement toward and away from the track, first spring means biasing said brackets toward said track, and retarding members mounted for camming movement on said brackets longitudinally and transversely of said track and spring loaded by second spring means toward said track.
10. Mechanism according to claim 9 in which said retarding member support brackets and said retarding members are mounted for movement in planes generally parallel to the plane of said drive member loop.
11. Mechanism according to claim 10 in which said belt is connected to the upper edge of said door.
12. Sliding door operating and supporting mechanism including a door supporting track to support a door in open and closed positions relative to an upright jamb, rollers spaced along said track and connected to the edge of the door, a drive shaft extending transversely of said track and having a reversible drive including a motor connected to the shaft, said mechanism being characterized by a drive pulley connected to said shaft, an idler pulley support longitudinally slidably mounted on said track and having an idler pulley rotatably mounted on said pulley support, spring means biasing said support and idler pulley away from said drive pulley, a flexible driving loop trained around said pulleys and urged to frictional driving engagement with said drive pulley by said spring means, means connecting a reach of said driving loop to said door, limit switches having operating elements positioned to be actuated by movement of said door to open and closed positions and adapted to be connected to said motor, a retarding plate support bracket fixedly located adjacent said track, a retarding plate movably connected to said support bracket and positioned to be cammingly engaged by one of said rollers as said door approaches closed position, second spring means biasing said retarding plate against camming motion by said one roller, means forming a cam connection between said retarding plate and said support bracket and arranged to permit disengaging motion of said plate from said one roller upon opening motion of said door, and third spring means biasing said plate on said bracket toward roller engaging position.
13. Mechanism according to claim 12 in which said means forming said cam connection has a dwell portion at one end to which said plate is urged by said third spring means.
14. Mechanism according to claim 12 in which the operating element of one of said switches is positioned to be actuated by said retarding plate upon movement of the plate by said roller against said second spring means.
15. Sliding door operating and supporting mechanism including a door supporting track to support a door in open and closed positions relative to an upright jamb, rollers spaced along said track and connected to the edge of the door, a drive shaft extending transversely of said track and having a reversible drive including a motor connected to the shaft, an idler pulley mounted in spaced relation to said drive pulley along said track, a flexible driving loop trained around said pulleys, means connecting a reach of said driving loop to said door, limit switches having operating elements positioned to be actuated by movement of said door to open and closed positions and adapted to be connected to said motor, a retarding plate support bracket fixedly located adjacent said track, a retarding plate movably connected to said support bracket and positioned to be cammingly engaged by one of said rollers as said door approaches closed position, spring means biasing said retarding plate against camming motion by said one roller, means forming a cam connection between said retarding plate and said support bracket and arranged to permit disengaging motion of said plate from said one roller upon opening motion of said door,

and second spring means biasing said plate on said bracket toward roller engaging position.

16. Mechanism according to claim 15 in which said cam connection has a dwell portion at one end to which said plate is urged by said second spring means.
